UNITED STATES PATENT OFFICE

2,222,703

PRESSURE RELIEF MEANS

Harley H. Bixler, Schenectady, N. Y., assignor to
General Electric Company, a corporation of
New York

Application June 12, 1937, Serial No. 147,917

5 Claims. (Cl. 220—89)

My invention relates to pressure relief means and more particularly to pressure relief means for use in refrigerating apparatus.

It is an object of my invention to provide an improved pressure relief arrangement for refrigerating machines of the hermetically sealed type.

A further object of my invention is to provide an improved pressure relief valve which is of simple construction, which is positive in operation, and which is economical to manufacture.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawing in which Fig. 1 is a side elevational view, partly in section, of a refrigerating machine provided with a pressure relief arrangement embodying my invention; Fig. 2 is an enlarged sectional view of an exhaust muffler having a pressure relief valve therein included in the refrigerating machine shown in Fig. 1, the pressure relief valve being shown in its initial position of operation; Fig. 3 is a fragmentary sectional view of the exhaust muffler and pressure relief valve shown in Fig. 2, the pressure relief valve being shown in its final position of operation; and Fig. 4 is a fragmentary perspective view, partly in section, of a modified form of the pressure relief valve shown in Figs. 2 and 3.

Referring to the drawing, in Fig. 1 I have shown a refrigerating machine of the household type provided with an hermetically sealed enclosing casing 10 formed of an upper casing section 11 and a lower casing section 12, the adjacent edges of these casing sections being welded together at 13 over a reinforcing ring 14. The casing sections 11 and 12 are preferably made of steel and are mounted on a removable top wall 15 of a heat insulated refrigerator cabinet. A refrigerant compressor 16 and an electric driving motor 17 therefor are arranged within the enclosing casing 10 on three vertical springs 19 equally spaced about the periphery of the frame of the driving motor 17. Intake and exhaust mufflers 20 and 21 are arranged within the enclosing

casing 10 and communicating respectively with intake and exhaust ports in the compressor 16 through conduits 22 and 23, respectively. The intake and exhaust mufflers 20 and 21 are provided in order to minimize the transmission of operating noises produced by the compressor 16 to the exterior of the enclosing casing 10. A lubricant reservoir 24 is formed in the lower casing section 12 and contains a body of lubricant therein which is recirculated from the lubricant reservoir 24 to the bearings and moving parts of the compressor 16 and the driving motor 17 during operation of the refrigerating machine. Also, a quantity of gaseous refrigerant is contained in the upper portion of the enclosing casing 10.

During normal operation of the refrigerating machine illustrated, gaseous refrigerant in the enclosing casing 10 is drawn into the compressor 16 through the intake muffler 20 and the conduit 22 and compressed and discharged into the exhaust muffler 21 through the conduit 23. The compressed refrigerant is conducted from the exhaust muffler 21 through a conduit 25 into an air cooled condenser 26 of the natural draft type supported about the enclosing casing 10 upon an annulus of fins 26a. The compressed refrigerant in passing through the condenser 26 is cooled and condensed into a liquid and then flows through a conduit 27 into a suitable float-operated flow-controlling device 28. Liquid refrigerant is supplied from the float-operated flow-controlling device 28 through a liquid supply conduit 29 to a cooling unit 30. The cooling unit 30 comprises a sheet metal evaporator of the flooded type which is supported from an inner liner 31 of the removable top wall 15 in a food compartment 32 formed in the refrigerator cabinet cooled by the refrigerating machine. The liquid refrigerant contained in the evaporator 30 is vaporized by the absorption of heat from the food compartment 32 and the vaporized refrigerant is collected in a cylindrical header 33 formed in the evaporator 30 which is normally maintained about one-half full of liquid refrigerant. The vaporized refrigerant which accumulates above the level of the liquid refrigerant in the header 33 is returned to the interior of the enclosing casing 10 through a suction conduit 34 which communicates with the header 33 above the normal liquid level therein. It will be noted that the discharge end 34a of the suction conduit 34 is located above the normal level of the body of lubricant con-

tained in the lubricant reservoir 24 formed in the lower casing section 12. The vaporized refrigerant returned to the enclosing casing 10 is again drawn into the compressor 16 through the intake muffler 20 and the conduit 22, and the cycle above described is continuously repeated until the food compartment 32 in which the evaporator 30 is located is cooled to the desired temperature. The conduit 23, the exhaust muffler 21, the conduit 25, the condenser 26, the conduit 27, the float-operated flow-controlling device 28 and the liquid supply conduit 29 constitute a relatively high pressure refrigerant connection between the compressor 16 and the evaporator 30, while the conduit 22, the intake muffler 20, the interior of the enclosing casing 10 and the suction conduit 34 constitute a relatively low pressure refrigerant connection between the compressor 16 and the evaporator 30.

As best shown in Fig. 2, the exhaust muffler 21 comprises a cylindrical muffler casing formed of a series of similar casing sections 35 of cup-shaped configuration, the casing sections 35 being secured together in nested relation. A plurality of muffle chambers 36 are formed in the muffler casing by end walls 37 of the casing sections 35, these muffle chambers communicate with each other through restricted openings 38 formed in the end walls 37 of the casing sections 35. An enlarged inlet passage 39 is formed in the end wall 37 of the casing section 35 disposed at the upper end of the muffler casing and one end of the conduit 23 is securely fastened in place therein. An enlarged outlet passage 40 is formed in the cylindrical side wall of the casing section 35 disposed at the lower end of the muffler casing and one end of the conduit 25 is securely fastened in place therein.

A diaphragm 41 normally having a concave cup-shaped configuration is secured in the open end of the casing section 35 disposed at the lower end of the muffler casing and constitutes an end wall thereof. A plate 42 is securely fastened in the open end of the casing section 35 disposed at the lower end of the muffler casing adjacent the diaphragm 41 and cooperates with the diaphragm 41 to form a relief chamber 43 therebetween. A substantially flat surface is formed on the diaphragm 41 adjacent the center thereof in order to provide a relatively weak area 41a therein. A member or pin 44 having a sharp end 44a disposed adjacent the relatively weak area 41a in the diaphragm 41 is carried by the plate 42. A relief passage 45 is formed in the plate 42 and communicates between the relief chamber 43 formed between the diaphragm 41 and the plate 42 and the interior of the enclosing casing 10.

During operation of the refrigerating machine, should the pressure in the muffle chamber 36 formed in the casing section 35 disposed at the lower end of the muffler casing, which muffle chamber constitutes a pressure chamber, exceed a predetermined abnormally high pressure due, for example, to the failure of the float-operated flow-controlling device 28, the concavity of the diaphragm 41 would be abruptly changed to move the relatively weak area 41a therein into puncturing engagement with the pin 44, as shown in Fig. 3. The abnormally high pressure condition existing in the relatively high pressure refrigerant connection between the compressor 16 and the evaporator 30 is then relieved by the flow of compressed refrigerant from the muffle chamber 36 adjacent the diaphragm 41 through the rupture 75 in the diaphragm 41, the relief chamber 43, and

the relief passage 45 in the plate 42 into the interior of the enclosing casing 10.

The peripheral edge of the cup-shaped diaphragm 41 is sealed to the inner surface of the cylindrical side wall of the casing section 35 disposed at the lower end of the muffler casing, which casing section constitutes a valve casing for the pressure relief valve, and is retained in position by the plate 42 which prevents sliding movement of the peripheral edge of the diaphragm 41. Thus, the diaphragm 41 is capable of moving with respect to the muffler casing only by bending outwardly into a substantially convex configuration and into puncturing engagement with the pin 44 upon the occurrence of a predetermined abnormally high pressure in the adjacent muffle chamber 36. Due to the normally concave configuration of the diaphragm 41, there is only a slight bending movement thereof towards the pin 44 as the pressure in the adjacent muffle chamber 36 increases, until the pressure in the adjacent muffle chamber 36 reaches a predetermined abnormally high value moving the diaphragm 41 into an unstable position which causes the concavity thereof to be abruptly changed to move the diaphragm into puncturing engagement with the pin 44. The substantially flat surface 41a is formed on the diaphragm 41 in alignment with the pin 44 in order to insure that the normally concave diaphragm will move into substantially uniform convex configuration, sloping from the peripheral edge towards the center thereof, and into puncturing engagement with the pin 44 when the diaphragm is moved from its unstable concave position into its convex configuration upon the occurrence of a predetermined abnormally high pressure in the adjacent muffle chamber 36. The abnormally high pressure required to move the diaphragm 41 into its unstable concave position and thence into puncturing engagement with the pin 44 is determined by the normal concavity, resiliency and thickness characteristics of the diaphragm 41, the diaphragm being designed to be moved into its unstable concave position and thence into puncturing engagement with the pin 44 upon the occurrence of a predetermined abnormally high pressure well above the normal operating pressures existing in the relatively high pressure refrigerant connection between the compressor 16 and the evaporator 30.

The fact that the refrigerating machine is rendered substantially inoperative when the pressure relief valve is operated, upon the occurrence of a predetermined abnormally high pressure in the relatively high pressure refrigerant connection between the compressor and the evaporator, is not objectionable as I have found that abnormally high pressures occur in refrigerating machines of this type very infrequently and only upon failure of some other part of the refrigerating machine requiring repair. As the refrigerating machine is hermetically sealed, it must be disassembled in any case in order to repair the part thereof which caused the abnormally high pressure condition and while the machine is disassembled a new exhaust muffler embodying the pressure relief valve described may be readily incorporated therein.

In Fig. 4 I have shown a modified form of the pressure relief valve which includes a member or pin 46 formed of half-round stock secured in a circular relief passage 47 formed in the plate 42 for puncturing the diaphragm 41, the remainder of the construction and the arrangement of the

pressure relief valve being otherwise the same as that described in connection with Figs. 2 and 3.

As the pin 46 is formed of half-round stock and secured in the circular relief passage 47 formed in the plate 42, the construction is somewhat simplified as it is only necessary to provide a single opening in the plate 42 during the course of manufacture. Furthermore, the pin 46 presents a somewhat sharper end 46a to the diaphragm 41 for rupturing the diaphragm 41.

While I have shown a particular embodiment of my invention, I do not desire my invention to be limited to the particular construction shown and described, and I intend in the appended claims to cover all modifications within the spirit and scope

of my invention.

What I claim as new and desire to secure by Letters Patent of the United States is:

1. A pressure relief valve comprising a valve casing having an inlet passage and a relief passage therein, means including a diaphragm normally having a concave configuration separating said passages, the surface of said diaphragm opposite the concave surface thereof being subjected to the pressure in said valve casing, and means including a member associated with and disposed adjacent the concave side of said diaphragm for puncturing said diaphragm to connect said passages, said diaphragm having a portion thereof so shaped that the concavity of said diaphragm abruptly changes for moving said diaphragm into puncturing engagement with said member upon the occurrence of a predetermined high pressure in said valve casing.

35 2. A pressure relief valve comprising a valve casing having an inlet passage and a relief passage therein, means including a diaphragm normally having a concave configuration separating said passages, the surface of said diaphragm opposite the concave surface thereof being subjected to the pressure in said valve casing, and means including a member associated with and disposed adjacent the concave side of said diaphragm for puncturing said diaphragm to connect said passages, said diaphragm having a portion thereof so shaped that the concavity of said diaphragm abruptly reverses for moving said diaphragm into puncturing engagement with said member upon the occurrence of a predetermined high pressure in said valve casing.

3. A pressure relief valve comprising a valve casing having an inlet passage and a relief passage therein, means including a diaphragm nor-

mally having a concave configuration separating said passages, the surface of said diaphragm opposite the concave surface thereof being subjected to the pressure in said valve casing, said diaphragm having a relatively weak area, and means including a member disposed adjacent the relatively weak area in said diaphragm on the concave side thereof for puncturing said diaphragm to connect said passages, said weak area of said diaphragm being so located that the concavity of said diaphragm abruptly changes for moving the relatively weak area in said diaphragm into puncturing engagement with said member upon the occurrence of a predetermined high pressure in said valve casing.

4. A pressure relief valve comprising a valve casing having an inlet passage and a relief passage therein, means including a diaphragm normally having a concave cup-shaped configuration separating said passages, the surface of said diaphragm opposite the concave surface thereof being subjected to the pressure in said valve casing, said diaphragm having a substantially flat surface adjacent the center thereof for providing a relatively weak area in said diaphragm, and means including a member disposed adjacent the relatively weak area in said diaphragm on the concave side thereof for puncturing said diaphragm to connect said passages, said relatively weak area causing the concavity of said diaphragm to abruptly change to move the relatively weak area in said diaphragm into puncturing engagement with said member upon the occurrence of a predetermined high pressure in said valve casing.

5. A valve construction comprising a valve casing, means including a diaphragm having a normally concave configuration forming pressure and relief chambers in said valve casing, said pressure chamber having inlet and outlet passages therein, the surface of said diaphragm opposite the concave surface thereof being subjected to the pressure in said pressure chamber, and means including a member associated with and disposed adjacent the concave side of said diaphragm for puncturing said diaphragm to connect said chambers, said diaphragm having a portion thereof so shaped that the concavity of said diaphragm abruptly changes for moving said diaphragm into puncturing engagement with said member upon the occurrence of a predetermined high pressure in said pressure chamber.
